UNITED STATES PATENT OFFICE.

ROBERT R. JONES, OF AKRON, OHIO, ASSIGNOR TO THE FIRESTONE TIRE AND RUBBER COMPANY, OF AKRON, OHIO, A CORPORATION OF OHIO.

APPARATUS FOR COATING AND DRYING FABRIC OR THE LIKE.

Application filed August 2, 1921. Serial No. 489,348.

This invention relates to an apparatus for coating and drying materials, particularly fabric, and is especially adapted, although not limited, to the coating of fabric with rubber and drying.

As is well known in the art, it is sometimes desirable to coat or saturate fabric, such as is incorporated in automobile tire casings, or for other purposes, with a solution of rubber in a volatile and often explosive solvent. The coated and saturated fabric is then dried so as to eliminate the solvent, the fumes of the solvent being recovered for reuse. Many forms of driers have been devised for this purpose, but, owing to the explosive character of the fumes derived from the drying fabric, the use of apparatus for this purpose has been attended with great danger to the operators. It also has been difficult to clean out the coating and drying device and to inspect the fabric while it is being treated without danger of explosion.

By the improved form of drying apparatus shown herein, I am enabled to obviate many of the difficulties heretofore encountered and to lessen the danger of explosion. In addition to these features, I have so constructed the drying apparatus that if an explosion should take place, there will be no danger to the operators by providing an easily opened vent at the top of the drying chamber, which usually projects above the building in which the drying apparatus is housed, through which vent the force of the explosion will be discharged.

While the invention is designed and will be described with relation to the saturation of fabric with a rubber solution, it is not limited to this particular work, but may be extended to other similar operations. It also will be understood that the design and proportion of the several parts of the apparatus may be modified or varied within the scope of the invention without departing therefrom or sacrificing any of the benefits of the invention.

In the drawings accompanying the application is shown one embodiment of the invention in which

Fig. 1 is a vertical section through the

coating and drying apparatus, a portion of the drying chamber being removed to reduce the height.

Fig. 2 is a side elevation, the upper part of the drying chamber being broken away to show the internal construction.

Fig. 3 is a plan view, the top of the tank being removed.

Fig. 4 is an enlarged section through the seal at the fabric outlet.

Fig. 5 is a side elevation of the parts shown in Fig. 4.

Fig. 6 is a cross section through a seal at the fabric inlet point of the drying chamber,

Fig. 7 is a side elevation thereof.

The material to be coated, in this case fabric, is mounted on a roll 1, located at any point, preferably outside of and below the drying chamber, it being understood that when one roll is exhausted, the leading end of a new roll is attached to the end of the former roll by any means, preferably by stitching.

The fabric which is indicated by the numeral 2 passes from the roll 1 over a rod 3 and under rolls 4 attached to a platform 5, the purpose of this device being to allow the loose end of the fabric to be supported on changing a roll, a trough 6, being added, if desired to receive the fabric.

The drying chamber, 7 may be in any suitable form, being here shown as a casing or shell, preferably oval in shape. The lower portion 8 of the chamber and the base may be of somewhat heavier construction than the upper portion, so as to minimize the liability of the chamber blowing out on the operators upon an explosion.

The drying chamber is supported on the floor 10 above the one on which the operators are working so that the base of the chamber is above the heads of the operators and they can move around beneath the drier to inspect the fabric, replenish the tank and perform such other duties as may be required.

From the base of the drying chamber there depends a housing 12, the lower ends of the walls carrying dipping rolls 13, which are immersed below the level of the coating solution 14. The coating solution is con-

- tained in a tank or vat 15, which surrounds the lower end of the housing 12, a narrow opening 16 being provided at one side for the admission of the fabric and a narrow 5 opening 17 being provided at the other side for inspection of the solution and for refilling purposes. The entrance to the interior of the chamber is closed by the liquid seal formed by the coating solution.
- 10 The fabric passes from the rolls 4 over a roll 18, and through the narrow passageway 16 into the liquid in the tank. It is depressed within the liquid by the rollers 13 and then passes up through the casing 12.
- 15 At a point above the liquid in the tank the fabric passes between suitable squeeze rolls 19 and 20 which force the solution into the fabric and remove any surplus.

These squeeze rolls may be of any preferred construction, and I may provide a steel roll at 19 and a hard rubber roll at 20, this combination operating satisfactorily. Pressure between the rolls may be adjusted by the hand wheels 21. Transparent windows 22 may be provided for observing the condition of the fabric as it leaves the squeeze roll.

The fabric now passes up into the drying chamber through the long narrow opening 23.

It is necessary at times to obtain access to the interior of the coating tank for various purposes, and to enable this to be done without admitting air to the drying chamber, 35 there are provided, at the opening 23, seals which may be operated to close upon the fabric and seal the chamber against the admission of any air. These seals are shown at 24 in Fig. 1, and in detail in Figs. 6 and 40 7, it being understood that in a broad view of the invention other types of seals may be substituted for those shown. It has been found, however, that the seal shown herein 45 operates satisfactorily and it will now be described.

On either side of the opening 23 are placed oblong box-like frames or casings 25, which face each other and are closed by a cover 26, having a long narrow opening 27 50 over the opening 23, the cover being braced by brackets 28. In the frames 25 are housed expansible sealing members 29, which are like expansible bags and so arranged as to expand outwardly and close 55 the entrance to the chamber. The front of the members 29 are formed of curved plates 30, usually of zinc, which are connected to the rear of the casing by fluted or accordion walls 31 of flexible metal such as brass. 60 Fluid pressure, water, or air, may be admitted to the members 29 through pipes 32, located at any suitable point. When it is desired to close the entrance to the drying chamber, the seals are expanded until they 65 press against the fabric, air being then pre-

vented from entering the casing and the gas being kept within the casing.

From the point at which the fabric enters the drying chamber it is led in a circuitous path, by means of rollers to be described, 70 until it is dried sufficiently to be taken out of the casing.

In passing over the circuitous or zig-zag path, the fabric passes over a plurality of rolls arranged in the top and bottom of the 75 casing. These rolls are designated by the numerals 33 to 39 inclusive in the order of travel. Certain of these rolls may be corrugated or of squirrel cage construction to prevent undue accumulation of the sticky 80 rubber on the roll. Arranged at the sides of the fabric are a number of radiators or heaters 40, which are maintained at the proper temperature to dry the fabric quickly and without injury to the coating or fabric. 85

The lower rolls 34, 36 and 38, instead of being mounted directly within the casing, are supported in troughs, or chambers, 41, depending below the casing, openings 42 being provided in the base of the casing 90 through which the fabric passes. Transparent windows 43 may be let into the sides of the troughs opposite the rolls for obtaining a view of the fabric as it passes through the drying chamber. By having the rolls 34, 36 95 and 38 arranged in the manner described, the condition of the fabric at all stages of drying may be determined without entering the casing. This is quite advantageous in the mechanism disclosed.

The fabric, after being dried, passes out of the drying chamber through passageway 44, which is also sealed to prevent admission of air at this point. The seals for this purpose are indicated by the numeral 45, and 105 while their construction may be varied or modified, a preferred form is shown in Figs. 4 and 5, and will now be described.

The sides of the vestibule or chamber below the opening 44 are closed by walls 46 110 and to these walls are attached angular plates or holders 47, obliquely disposed as shown in Fig. 4. Below the plates 47 are arranged pressure plates 48, which are forced upwardly by screws 49, engaging 115 lugs 50, which are in turn fastened to the holders 47 by bolts 51. Between the holders 47 and the plates 48 are secured wipers or seals 52, which project outwardly and contact the fabric making an air tight seal. 120 These wipers or seals are of felt and are provided with thin flexible brass plates 53, against which the fabric rubs.

Attached to the side plates 46 are holders 54, provided with horns or fingers 56. Secured to the lower side of the holders 54 are yokes 57 supported and adjusted by wing nuts 58. Secured to the framework by the parts 54 and 57 are troughs or tubes 59, which face each other, the facing sides be- 125 130

ing opened so that the troughs are approximately three-quarters round. In the trough or pipes are seated tubes 60 of rubber or some other expandible substance, which tubes 5 are intended to be expanded by air or other fluid admitted through valves 61. The major portion of the expandible tubes are confined by the pipes 59 but the free or open portion of the tubes bear against the 10 depending edges of the seals or wipers 52 and press them against the fabric 2.

The form of sealing means described makes an effective closure for the exit opening of the casing, and while the invention is 15 not limited to the exact form of sealing device as shown, this form has operated satisfactorily and has proven highly successful in preventing the admission of air to the casing and the egress of the gas from the 20 casing.

From the yielding wipers 52 the fabric 2 passes under a roller 62, over an adjustable spreading roller 63 to the wind-up 64.

The atmosphere of the interior of the 25 drying chamber is constantly changed, fresh gas being introduced through an inlet 65, and the gas thoroughly saturated with the volatile solvent being withdrawn at 66. The gas in the interior of the chamber travels 30 in the opposite direction from the passage of the fabric and as it becomes heavy as it is saturated with the volatile solvent, the point of withdrawal of the gas is at the bottom of the chamber.

35 In order to prevent the occurrence of explosions in the chamber, the gas to fill the chamber may be some inert gas, which will make a non-explosive mixture.

In case sufficient air gets within the 40 chamber so as to form an explosive mixture, the apparatus is so designed that should the mixture become ignited, the force of the explosion will be expended in a direction away from the workmen. To insure this result, 45 besides making the lower part of the chamber of heavier material, so that the upper part will give way before the lower part, there is provided a plurality of easily movable covers which will be blown off the top 50 of the drying chamber.

At a number of points in the top of the 55 drying chamber 7, there are located pipes or stacks 67 surrounding flanged openings 68. Over these openings are placed covers or bells 69, which may be arranged to be raised by ropes or cables 70. These covers may be raised when it is desired to clean out the drying chamber.

In addition, larger openings 71 may be 60 constructed in the top of the chamber, which are closed by covers or trap doors 72. Over the top of the casing a level of water 73 is maintained which operates as a seal for the top of the chamber, as will be readily understood.

Any suitable means may be devised for driving the various rollers in the apparatus. One form is shown in the drawings in which 74 represents a reversible motor, which drives through suitable gearing a jackshaft 70 75 by two-speed drives 76 and 77 arranged to be coupled to the shaft by a shiftable clutch 78. From the jack shaft 75 is driven the power shaft 79, which by suitable chains or belts drives the shafts of one of the squeeze rolls and any number of the rolls 34, 36 and 38 as may be found necessary or desirable. The wind-up roll 64 may be driven from the same source. The driven devices are not shown in detail as they may be constructed in any suitable manner as good engineering practice may dictate.

From the description which has been given of the apparatus, it will be seen that a safe and workable arrangement has been produced by means of which the hazardous operation of drying fabric coated with a volatile solvent may be carried out without danger to the operators. By elevating the drying chamber the operators may safely move 85 below the drying chambers and by providing the depressed rolls 34, 36 and 38 with the accompanying windows, the work may be inspected at all times without necessitating access to the interior of the chamber. The 90 closure 24 enables the coating tank to be isolated from the remainder of the drying chamber for cleaning or other purposes without admitting air to the interior which is a valuable feature of the invention. The seal 100 45 at the outlet effectually prevents the admission of air at this point. The construction of the easily removable covers 69 and 72, together with the lighter construction of the upper part of the drying chamber, insures any explosion which might occur in the casing finding a vent out of the top thereof without chance of injury to the operators beneath the chamber, as the covers specified constitute easily ruptured closures 105 for the several openings.

Very satisfactory results have been derived from the use of a drying chamber constructed in the manner shown, and a large percentage of the volatile solvent has 110 been recovered from the gas withdrawn through the pipe 66.

The working parts of the apparatus are all below the drying chamber and are easy of access. The inlet and outlet seals are 120 simple and easily operated. Other advantages and improved results are obtained, and the invention is not limited to the exact form shown and described.

I claim:

1. An apparatus for coating and drying fabric or the like, comprising a drying chamber, a coating chamber, a passageway being provided from the coating chamber to the drying chamber, an expandible seal 130

- adapted to extend across the passageway and close it, and means for controlling the expansion of the seal.
2. An apparatus for coating and drying fabric or the like, comprising a drying chamber, a coating tank outside said drying chamber, a passageway being provided from the tank to the chamber, walls about said passageway extending within the liquid in the tank to form a seal and a second seal in the passageway above the tank, and means to operate the second seal to close the passageway.
3. An apparatus for coating and drying fabric or the like, comprising a drying chamber, a coating tank outside said drying chamber, a passageway being provided from the tank to the chamber, walls about said passageway extending within the liquid in the tank to form a seal, squeeze rollers in the passageway, and a second seal in the passageway above the tank and means to operate the second seal to close the passageway.
4. An apparatus for coating and drying fabric or the like, comprising a drying chamber, a coating tank outside of said drying chamber, a passageway being provided into the drying chamber, a housing about the passageway and extending into the tank and a sealing device in the passageway, said sealing device being movable to close the passageway.
5. A drying chamber for fabric or the like, having a passageway through which fabric is admitted to the chamber, and an expandible seal over the passageway which may be expanded to grip the fabric and close the passageway.
6. A drying chamber for fabric or the like, having a passageway through which fabric is admitted to the chamber, and a sealing device over the passageway which may be operated to close upon the fabric and shut the passageway, said sealing device comprising an expandible bag and means to expand the bag by fluid pressure.
7. A drying chamber for fabric or the like, having a passageway through which fabric is admitted to the chamber and a sealing device over the passageway which may
- be operated to close upon the fabric and shut the passageway, said sealing device comprising a fluted container and means to expand the fluted container by fluid pressure.
8. A drying chamber for fabric, comprising a casing, means for supporting the chamber so that the base is above the operators, means for conducting the fabric below the base of the chamber as it is subjected to the drying process, and means adjacent the conducting means for permitting an inspection of the fabric during the drying process without opening the drying chamber.
9. A drying chamber for fabric, comprising a casing, a portion of the casing being of lighter construction than the remainder, openings in the lighter portion of the casing, and easily ruptured closures for said openings.
10. A drying chamber for fabric, comprising a casing elevated above the working floor, means for conducting the fabric below the base of the casing and for permitting inspection thereof without entering the casing, the upper portion of the casing being of lighter construction than the base, the top of the casing having openings therein and easily ruptured closures for said openings.
11. In a drying apparatus, having means for supporting and guiding fabric and a passageway through which the fabric leaves the apparatus, and a seal at the passageway, said seal comprising wipers which bear against the fabric and resilient means for pressing the wipers against the fabric.
12. In a drying apparatus, having means for supporting and guiding fabric and a passageway through which the fabric leaves the apparatus, and a seal at the passageway, said seal comprising wipers which bear against the fabric and fluid expansible means for pressing the wipers against the fabric.
13. In an apparatus for coating and drying fabric, an elevated casing in which the fabric is led in a circuitous path, a tank, and means for guiding the fabric during a portion of its travel, said tank and guiding means being located on the under side of the casing and outside of the bounds thereof.

ROBERT R. JONES.
